UNITED STATES PATENT OFFICE.

JOSEPH W. DAVIDSON, OF CINCINNATI, OHIO.

DESIGN FOR A WALL-BRACKET OR CANDELABRUM FOR ELECTRIC AND OTHER
ILLUMINATION.

57,964.

Specification for Design.

Patented May 24, 1921.

Application filed October 25, 1920. Serial No. 419,544. Term of patent 14 years.

To all whom it may concern:

Be it known that I, JOSEPH W. DAVIDSON, a citizen of the United States of America, residing at Cincinnati, in the county of Hamilton and State of Ohio, have invented a new, original, and ornamental Design for a Wall-Bracket or Candelabrum for Electric and other Illumination, of which the following is a specification, reference being had to the accompanying drawing, forming part thereof.

In said drawing, Figure 1 is a front elevation of the wall bracket or candelabrum for electric and other illumination, and Fig.

2 is a sectional side elevation taken on the dotted-line 2, 2, of Fig. 1. Both of these views are presented in order to best show my new design in its preferred form, such preferred form including a mirror or reflecting surface in the main upper part of the wall plate or back of the bracket, but not to be taken or considered as essential to the carrying out of my design herein.

I claim:—

The ornamental design for a wall bracket or candelabrum for electric and other illumination, as shown and described.

JOSEPH W. DAVIDSON.
